FIG. 4. INVENTOR.

Le Baron C. Colt,
By Wilmot H. Thurston,

ATTORNEY.

UNITED STATES PATENT OFFICE.

LE BARON C. COLT, OF BRISTOL, RHODE ISLAND.

SOLE-ROLLING MACHINE.

1,102,389.

Specification of Letters Patent.

Patented July 7, 1914.

Application filed July 2, 1908. Serial No. 441,665.

To all whom it may concern:

Be it known that I, LE BARON C. COLT, of Bristol, in the county of Bristol and State of Rhode Island, have invented certain new and useful Improvements in Sole-Rolling Machines; and I do hereby declare the following specification, taken in connection with the accompanying drawings, forming a part of the same, to be a full, clear, and exact description thereof.

10 The invention relates to a machine which is more particularly adapted for use in connection with the manufacture of rubber-shoes or shoes composed of rubber and fabric. In 15 the manufacture of such shoes the several operations commonly performed after the shoe has been lasted consist in first applying what is known as the rag-filling sole to fill the space between the in-turned edges of the 20 lasted upper; then applying cement to the shoe along the edges thereof; then applying the toe-tip, the heel-tip and the foxing; then applying what is known as a cloth-filling sole to fill the space between the in-turned 25 edges of the foxing; and finally applying the out-sole.

In applying the rag-filling sole, the cloth-filling sole and the out-sole it is required in each case that the sole when applied shall 30 be rolled into firm and close contact with the part immediately beneath the same. Heretofore the several operations above set forth, including the rolling of the sole, have been performed entirely by hand, the rolling 35 operation being performed by the operator by means of a hand-roller.

The object of the present invention is to provide a machine or apparatus which will serve to automatically effect the requisite 40 rolling of the sole upon the lasted shoe, and thereby dispense with the operation of hand-rolling.

To that end the invention consists primarily in the combination, with a traveling 45 carrier adapted to receive a lasted shoe, of a pressure-roller arranged and adapted to act upon the lasted shoe and roll the sole thereon as said lasted shoe is carried by said movable bed past said pressure-roller.

50 The invention further consists in the combination, with a pressure-roller, of a traveling carrier adapted to receive a series of lasted shoes and carry the same successively past said pressure-roller, whereby, while a 55 sole is being rolled upon one of said lasted shoes, another lasted shoe with a sole ap-

plied thereto may be placed in position on the traveling carrier in advance of the pressure-roller.

The invention further consists in certain 60 combinations and arrangements of parts to be hereinafter described and claimed.

Referring to the drawings, Figure 1 is a side elevation of a machine or apparatus embodying the invention. Fig. 2 is a plan 65 view thereof. Fig. 3 is an end view. Fig. 4 is a section on the line *a—a* of Fig. 1.

The machine comprises a suitable frame composed of a series of uprights 1, 1, 1, with connecting bars 2 connecting said uprights. 70 Mounted in suitable bearings at or near one end of the machine is a driving shaft 3 which may be provided with tight and loose pulleys 4 and 5. Secured to said shaft 3 is a sprocket-wheel 6, and mounted in suitable 75 bearings at the opposite end of the machine is a shaft 7 to which is secured a corresponding sprocket-wheel 8.

9 is the traveling carrier, which in the machine shown is in the form of an endless 80 belt which extends around and is engaged by the sprocket-wheels 6 and 8. As shown in the drawings, the endless conveyer 9 comprises a series of carriages 10, each carriage consisting of a body portion 11 with two 85 axles 12, 12, secured thereto, said axles being provided with wheels 13 adapted to run on the track formed by the upper ends of the uprights 1 and by the connecting bars 2, said wheels being preferably flanged as 90 shown in the drawings. The adjacent carriages are connected together by suitable links 14, one on each side. The wheels 13 also constitute the means by which engagement of the conveyer with the sprocket-wheels is made, said wheels engaging suitable forks 15 formed on said sprocket-wheels. Each of the carriages 10 or the body portion 11 thereof is provided with suitable pins 16 to engage the usual holes in 100 the last.

Rigidly secured to the central uprights 1 are two arms or brackets 17. Pivoted to the upper ends of said arms is a U-shaped frame 18, the cross-piece of which is bent upward 105 to form a yoke or support 19 upon which is placed or secured a pressure-weight 20. As shown in the drawings, the yoke 19 is provided with a projecting pin 21 which engages a corresponding hole formed in the 110 bottom of the weight.

22 is the operating roll, the axle 23 of

which is mounted in suitable bearings in the U-shaped frame 18. In order to arrest or limit the downward movement of the U-shaped frame carrying the operating roll, two supports 24 are provided, one on each side of the machine, said supports being in line with and adapted to engage projections 25 on the side bars of the U-shaped frame. Preferably the supports 24 are in the form of spiral springs, as shown in the drawings.

26 represents the series of lasted shoes in position on the endless belt 9.

The operation of the machine or apparatus above described is as follows: Assuming that the operation to be performed by the machine shown in the drawings is the rolling on of the rag-filling sole, so called, and understanding that the endless belt 9 is continuously moving, the operator applies to the lasted shoe a suitable rag-filling sole in proper position, and then places the lasted shoe with such rag-filling sole in position on the pin 16 of one of the carriages 10 in advance of the pressure-roll 22. As the endless belt travels along, the toe of the lasted shoe will be brought into engagement with the under side of the operating roll 22, which roll will, as the lasted shoe is carried thereunder, be pressed against the rag-filling sole by the action of the weight 20 and will operate to roll said rag-filling sole into close contact with the in-sole beneath the same. When the lasted shoe has passed from beneath said roll 22, the downward movement 35 of said roll will be arrested by the engagement of the projections 25 with the supports or springs 24 in a position where the toe of the next lasted shoe to be brought along by the endless conveyer will engage the operating roll below the axis thereof and so that by the continued movement of said next lasted shoe, the roll will be sufficiently lifted to enable the shoe to pass beneath the same, the roll acting thereon with a pressure due 40 to the weight 20 referred to. When the lasted shoe has passed beyond the operating roll it may then be taken off of the endless belt for the performance of the next operations thereon, as for example, cementing, 45 applying the heel and toe tips and the fox-ing.

As will be seen, the rolling of the sole upon the shoe in the machine or apparatus above described is effected by the joint action 55 or coöperation of the pressure-roll and the endless bed, said movable bed serving to carry the lasted shoe beneath said pressure-roll and to cause said pressure-roll to act upon the sole from one end of the shoe to 60 the other, as said shoe is carried thereunder. It will thus be seen that the operation of rolling on the sole is performed entirely automatically and without any hand operation or intervention. It will also be seen 65 that the operation of rolling on the sole is

greatly facilitated by reason of the fact that not only is the operation automatically performed, but also because while a sole is being rolled on one lasted shoe by the machine the operator may be applying a sole to another lasted upper and placing it in position on the movable bed.

It will be understood that so far as the broad features of the invention are concerned the movable bed, instead of being in the form of an endless belt continuously traveling in one direction, as shown, may be a reciprocating bed which travels back and forth beneath the pressure-roller. It is preferred, however, to employ a movable bed which is in the form of an endless belt as shown, because with such endless belt continuously traveling in one direction no time is lost and the soles may be rolled on one lasted shoe after another practically without interruption.

While in the foregoing description reference has been made particularly to the rolling on of a rag-filling sole, so called, it will be understood that the machine described 90 may be employed for rolling on any other sole which enters into the make-up of the shoe, as for instance, the cloth-filling sole or the out-sole.

While the contour of the operating roll is 95 not material to the present invention, it is preferred to make said roll more or less concave, as shown in Fig. 3, but it is to be understood that the contour of the roll is to be such as may be best adapted for the particular sole which is to be operated upon.

While in the machine shown in the drawings a weight is employed for producing the necessary pressure upon the operating roll, it will be understood that, if desired, a 105 spring may be employed in place of such weight.

What I claim as my invention and desire to secure by Letters Patent is:

1. A machine for rolling soles on rubber 110 shoes comprising an endless belt adapted to receive a lasted shoe, and a swinging frame carrying a pressure-roller adapted to roll a sole on said lasted shoe as it is carried along by said endless belt. 115

2. A machine for rolling soles on rubber shoes comprising an endless belt adapted to receive a lasted shoe and transport the same from one point to another in the same plane, and a swinging frame carrying a pressure-roller adapted to roll a sole on said lasted shoe as it is carried along by said endless belt. 120

3. A machine for rolling soles on rubber shoes comprising an endless belt adapted to receive a series of lasted shoes, and a swinging frame carrying a pressure-roller adapted to roll soles on said lasted shoes successively as they are carried along by said endless belt. 125

4. A machine for rolling soles on rubber 130

shoes comprising an endless belt adapted to receive a series of lasted shoes and transport the same from one point to another in the same plane, and a swinging frame carrying 5 a pressure-roller adapted to roll soles on said lasted shoes successively as they are carried along by said endless belt.

5. A machine for rolling soles on rubber shoes comprising an endless belt composed

of a series of carriages adapted to receive a 10 series of lasted shoes, and a swinging frame carrying a pressure-roller adapted to roll soles on said lasted shoes successively as they are carried along by said endless belt.
